United States Patent Office

Des. 228,977

Patented Nov. 6, 1973

228,977

PROTECTIVE GLOVE

Walter J. Kanicki, 2011 3rd St.,
Bay City, Mich. 48706

Filed Aug. 5, 1971, Ser. No. 169,601

Term of patent 14 years

Int. Cl. D2—06

U.S. Cl. D2—361

FIG.1

FIG.3

FIG. 1 is an elevational view of the back of a protective glove showing my new design;

FIG. 2 is an elevational view of the palm side thereof; and

FIG. 3 is an enlarged isometric view.

I claim:

The new and ornamental design for a protective glove, as shown.
